LIQUID DISPENSING DEVICE

Jacob C. Miller, Whitefish Bay, Wis.

Application December 18, 1933, Serial No. 702,885

6 Claims. (Cl. 221—102)

This invention relates to liquid dispensing devices.

It is a primary object of the invention to provide a container for liquid having a novel and efficient means for dispensing a liquid other than by tilting or inverting the container.

More specifically, it is an object of this invention to provide for a liquid dispensing bottle, a manually operable pump device and reservoir fitted into the mouth of the bottle and adapted to seal the bottle when the device is not manually operated.

Another object is to provide a liquid dispenser for bottles, which may be designed to dispense a predetermined amount of liquid by manually regulating the number and extent of plunger strokes, whereby to effect a saving in liquid to the user of this controlled device.

A further object is to provide a liquid dispensing device which may be easily applied to standard bottles and which will be simple and cheap to manufacture, and which will last for a long period of time without repair.

Other objects will appear as the description progresses.

In the drawing:

The drawing is a vertical sectional view taken axially through a bottle equipped with a stopper embodying the device.

The container 1 for the purpose of illustration comprises a bottle provided with a threaded neck 2. Threaded to the bottle neck 2 is a centrally apertured cap nut 3 of sufficient size to accommodate centrally apertured cap 5 having at its lower end a flange 6 engaging the marginal area adjacent the central aperture 4 of threaded cap nut 3. Engaging the inner end of the apertured cap 5 is a sealing washer 10 seated upon the end of the bottle neck 2. The apertured cap 5 has a reservoir 11 in its outer end communicating with the aperture 15 in the cap 5.

Inserted in the aperture 15 of the cap 5 is a cylindrical plunger 16, bevelled intermediate its ends at 17 to provide a reduced end 8 having a diameter less than the diameter of the aperture 15. The plunger 16 is recessed or cupped at end 8 to receive either the finger of an operator or the end of an orangewood stick or other manicuring implement. The plunger 16 extends slightly above the plane of the upper margin of the cap 5 to permit a longer stroke of the plunger than would otherwise be possible. The plunger 16 is shouldered at 24 to provide a piston end 19 slidably fitting within the elongated tube 25 carried by cap 5. The tube 25 is re-

ceived in the recess 21 and is secured therein by engagement with the wall thereof. The tube 25 is substantially concentric with the aperture 15 to permit the bevelled portion 17 to engage the margin of the aperture 15 of the cap 5.

The piston end 19 is centrally recessed at 22 to receive a centrally apertured bushing 26 having a flange 27 engaging the inner end of the plunger 16. The recess 22 extends in reduced size at 23 to communicate with the radial apertures 28 which communicate with the annular space 58 between the plunger 16 and the tube 25. A small aperture 59 is provided through which, from time to time, air may enter the bottle. It is too small an opening to divert any appreciable proportion of the liquid being pumped. A ball valve 30 is seated in inner bevelled face 31 of bushing 26.

Bushing 26 is held in position on the plunger 16 by means of a helical spring 32 engaging the flange 27 of the bushing 26. The helical spring 32 is positioned at its end on the flange 41 of the centrally apertured bushing 42. The bushing flange 41 is seated on the inner end of the centrally apertured plug 43, which is provided with a valve seat 53 upon which a ball valve 54 is seated.

The device is particularly adapted for use by manicurists. Its use in this field will exemplify its more general utility.

Assuming the container 1 has a supply of liquid, the operator desiring to use this device will ordinarily operate the plunger 16 against the compression of spring 32 by pressing upon the cupped end thereof with an orangewood stick wrapped at its end with cotton to be moistened in the contents of the bottle.

The movement of plunger 16 causes pressure to be exerted on the surface of the liquid confined in the tube 25 thus firmly seating valve 54 and causing the liquid in the tube to flow past the valve 30 into the recess 22 and from there into the space 58.

When the plunger 16 is released for vertical movement the helical spring 32 will return the plunger 16 to its original position. At the beginning of this return movement the valve 30 reseats and valve 54 opens admitting liquid to tube 25. Liquid in the chamber 58 will, by the upward movement of the plunger 16, be pushed on through aperture 15 in cap 5 and thus into recess 11. The cotton on the stick used to manipulate the plunger will be moistened in the liquid maintained in recess 11 by the seating of the plunger surface 17 against the closure 5 at the lower end of passage 15.

I claim:

1. In a liquid container having an apertured neck, the combination with an apertured cap secured thereto, of a tube secured to the inner face 5 of said cap co-axially with said aperture, a plunger reciprocable in said tube, said plunger having a piston portion, a plunger portion of less diameter than said piston portion and a second portion of less diameter than said plunger portion 10 extending through said aperture of said cap and providing a valve portion between said plunger portions adapted to seat upon the margin of said aperture, said plunger also having a recess in its piston portion communicating with the space between said plunger portions and said tube, valve means in said recess, valve means at inner end of said tube, and a spring disposed between said means whereby to normally hold valve portion of said plunger in contact with said cap.
2. In a liquid container having an apertured neck, the combination with an apertured cap secured thereto, of a tube secured to the inner face of said cap co-axially with said aperture, a plunger reciprocable in said tube, said plunger 15 having a piston portion, a plunger portion of less diameter than said piston portion and a second portion of less diameter than said plunger portion extending through said aperture of said cap and providing a valve portion between said plunger portions adapted to seat upon the margin of said aperture, said plunger also having a recess in its piston portion communicating with the space between said plunger portions and said tube, valve means in said recess, valve means 20 at inner end of said tube, and a spring disposed between said means whereby to normally hold the valve portion of said plunger in contact with said cap, said tube being provided with a relatively small aperture communicating with the space between said plunger portion and said tube, whereby to relieve liquid in said space.
3. A liquid dispensing device comprising a bottle closure having a face to which liquid is to be delivered, said closure providing an aperture 25 leading to said face, a tube extending downwardly from said closure communicating with said aperture, a check valve in said tube, a displacement piston in said tube provided with a valved opening, and a rod of reduced diameter connected with said closure and having a space between 30 it and said tube with which said valved opening communicates, said rod extending through the aperture of said closure member for manipulation of said piston in the elevation of liquid through said space and aperture and outside of said rod to the aforesaid face of said closure member.
4. The combination with a closure for a container having a reservoir recess in its top and an apertured opening to said recess, of a pump including a tubular casing connected with said closure and communicating with said recess through said aperture, said pump including a plunger having an operating stem projecting through said aperture and a spring support for said plunger and stem, and valves whereby the liquid displaced by said plunger is delivered through the aperture in which said stem operates.
5. A device of the character described, comprising a closure applicable to the mouth of a container having a reservoir recess in its upper 20 surface and an aperture opening to the bottom of said recess, a pump casing mounted on said closure and extending downwardly therefrom into the contents of a container to which said closure is applied, a plunger reciprocable in said 25 casing and including a reduced stem portion projecting through the aperture with substantial clearance, said plunger being adapted to seat against said closure at the lower end of said aperture as a valve, a spring yieldably supporting said plunger, a foot valve carried by said casing, and valve means carried by said plunger for permitting the flow of liquid from said casing about said plunger during the downward stroke of the plunger only, whereby said plunger on 30 its upward stroke will elevate liquid through said aperture to the reservoir recess of said closure.
6. A device of the character described comprising a bottle closure having a reservoir recess and an aperture opening through said closure from the bottom of said recess, of pumping means 35 arranged to deliver its output through said aperture and including an operating stem substantially smaller than said aperture projecting therethrough for the actuation of said pumping means, said stem having a cavity at its free end adapted to maintain an actuating stick in contact with the stem.

JACOB C. MILLER.
